UNITED STATES PATENT OFFICE.

JOHN G. HYNDS, OF NEW YORK, N. Y., ASSIGNOR OF NINE-TENTHS TO RODERICK BEGG,
OF NEW YORK, N. Y.

ABDOMINAL SUPPORTER.

1,126,765.

Specification of Letters Patent.

Patented Feb. 2, 1915.

Application filed November 3, 1913. Serial No. 798,815.

To all whom it may concern:

Be it known that I, JOHN G. HYNDS, a citizen of the United States, residing at New York, in the county of New York and the State of New York, have invented certain new and useful Improvements in Abdominal Supporters, and do hereby declare the following to be a full, clear, and exact description of the invention, such as will enable others skilled in the art to which it appertains to make and use the same.

This invention relates to wearing apparel, and more particularly to supporters.

An object of this invention is to provide an abdominal support of an improved form, which provides for the formation of a tab which may be made integral, or detachable, and this tab may be passed through the crotch of a wearer.

A further object of this invention is to provide a supporter which may be worn by athletes, or may be used as a supporter for catamenial napkins.

Further objects will be apparent from the following specification, appended claim, and drawings thereof, in which,

Figure 1 is a perspective view of a supporter showing the tab fastened in dotted lines, Fig. 2 is an elevation of the supporter from the rear, and, Fig. 3 is a perspective view of a modified form of the invention.

Referring to the drawings, in which, similar reference numerals indicate similar parts through the several views, there is shown a band which encircles the waist or hips of a wearer, and from this band depends a tab which may be passed through the crotch of the wearer, when, the free end of this tab is secured to the lower edge of the band in the front thereof. The band comprises sections 10 which are made of elastic material, and these sections are connected at their ends to gores 11 and 12, of which, the gore 11 is of non-elastic material, and has a tongue 13 formed on the lower edge. The tongue 13 may have eyes or other fastening means 14 secured thereto, which form parts of fastening means to be hereinafter described.

The gore 12 is made of similar material to the gore 11, but this gore has an exten-

sion from the lower end, which forms a tab 15, and this tab may be of sufficient length to pass through the crotch of a wearer to be fastened to the tongue 13. The tab 15 is shaped to conform with curvature of a body, and has hooks 18 secured to the end thereof, so that when the tab is to be secured in place, the hooks 18 engage the eyes 14 and hold the tab in place. The gore 12 has the placket 16 formed therein to enable the application and removal of the band, and this placket is closed or permitted to open by tightening or loosening the lace 19.

Fig. 3 of the drawing shows the band provided with a sanitary napkin, and in this instance, the tab 15 does not pass through the crotch of a wearer, but terminates at a desired point and has a hook 17 secured thereto, to which hook, one end of a napkin 20 is secured as by passing an eyelet 21 over the hook 17, and then passing the napkin across the body to permit the eyelet 22 being hooked upon the hook 23. In this case, the napkin may be of ordinary make, and may be economically made hence discarded without great loss.

Modifications may be made within the scope of this invention without departing from the spirit thereof, and the drawings are submitted for illustrative purposes only.

Having thus described my invention, I claim,

In an article of the class described, a band comprising sections of elastic material, front and back gores of non-elastic material, said front and back gores tapering upwardly from the bottom edges of said elastic sections, and said front and back gores extending below the lower edge of said elastic sections, the back gore having a placket formed therein, which extends below the lower edge of said elastic sections, a lace for closing said placket, and a tab carried by said back gore to extend across under said band and means for attaching said tab to the lower edge of said front gore.

JOHN G. HYNDS.
